(57) **CLAIM**

The ornamental design for a beam scale, as shown and described.

DESCRIPTION

FIG. 1 is a front right perspective view of a beam scale according to an exemplary embodiment of the present invention.

FIG. 2 is a front elevational view of the beam scale.

FIG. 3 is a back elevational view of the beam scale.

FIG. 4 is a right side elevational view of the beam scale.

FIG. 5 is a left side elevational view of the beam scale.

FIG. 6 is a top plan view of the beam scale; and,

FIG. 7 is a bottom plan view of the beam scale.

The broken line showing is for illustrative purposes only and forms no part of the claimed design.
